UNITED STATES PATENT OFFICE.

PAUL C. BALDUS, OF MILWAUKEE, WISCONSIN.

WRENCH.

Application filed April 23, 1920. Serial No. 376,124.

To all whom it may concern:

Be it known that I, PAUL C. BALDUS, a citizen of the United States, and resident of Milwaukee, county of Milwaukee, and State of Wisconsin, have invented new and useful Improvements in Wrenches, of which the following is a description, reference being had to the accompanying drawings, which are a part of this specification.

10 The invention relates to a valve adjusting device and more particularly to a pair of tappet or valve rod adjusting tools, such as wrenches, operating in parallel planes so that two members may be adjusted with 15 relation to each other and then locked by screwing up a lock nut with another tool.

The object of the invention is to provide a simple and economical wrench construction in which while the wrenches are 20 posed in spaced relation parallel to each other they are relatively movable with respect to each other to engage the nut portions of the members to be secured in adjusted relation. In many instances where 25 devices of this character are used the nut portions of the members to be adjusted are of the same size and by the present construction the wrenches for engaging these portions may be duplicates of each other made 30 from the same die. This feature is of importance where the devices have to be made to supply the demand for different sizes.

A further object of the invention is to 35 provide an efficient construction for connecting the spaced wrenches together including an adjustable linkage of simple construction.

The invention further consists in the several features hereinafter set forth and more particularly defined by claims at the 40 conclusion hereof.

In the drawings: Fig. 1 is a plan view of a device embodying the invention; Fig. 2 is a side elevation thereof; Fig. 3 is a section taken on the line 3—3 of Fig. 1; Fig. 4 is a 45 detail plan view of a modified form of construction; Fig. 5 is a detail sectional view taken on the line 5—5 of Fig. 4, showing a modified form of connection; Fig. 6 is a section similar to Fig. 5 showing another 50 form of connection.

In the drawings the numerals 7 and 8 designate the wrenches or holding members, the wrench 7 being designed to engage the head of a member 9, such as a bolt, and the 55 wrench 8 engaging the flat faces 10 of a member 11, said members 9 and 11 being ad-

justable with respect to each other and secured in adjusted position by means of a lock nut 12 on the bolt 9 which is tightened up by a third wrench 13. These wrenches 60 may be double ended, as shown in Fig. 1, so that two different sizes of wrenches may be embodied in a single device and both wrenches can be made from the same die where the nut portions of the members to be 65 engaged are the same size.

In Figs. 1 to 3 inclusive I have shown a linkage connection between the wrenches consisting of a pair of links 14 and 15 connected together by a screw bolt 16, while in 70 Fig. 4 I have shown a single link 17 having a slotted end 18. In both instances one end of the linkage connection is secured in spaced parallel relation with the wrench 8 by means of a bolt 19 clamped to said wrench 75 8 by its head and a nut 20 and carrying an adjustable nut 21, a lock nut 22 and a wing nut 23. The other end of the linkage connection is secured to the wrench 7 by means of a bolt 24 passing therethrough and wing 80 nut 25.

In Figs. 1 to 3 inclusive the free end of the link 14 is clamped between the nuts 21 and 23, the nut 21 having been previously adjusted to the proper distance on the bolt 85 19 and locked by the nut 22, and the free end of the link 15 is clamped between the wrench 7 and the nut 25.

In Fig. 4 the end 26 of the link 17 is clamped between the nuts 21 and 23 in a 90 similar manner to that of the link 14 so as to be adjustably secured in spaced relation to the wrench 8 and the bolt 24 passes through the slotted end of said link to which it may be secured by the nut 25. 95

Where an adjustable spacing of the wrenches is not desired the link 17 or the link 14 may be used to space the wrench 8 a fixed distance from the wrench 7 by providing a depending end 27 on the link, riveted or otherwise suitably secured to the wrench 7, as shown in Fig. 5, or by providing a block 28 as shown in Fig. 6.

In the use of the device shown in Figs. 1 to 4 inclusive the spaced adjustment of the 105 wrenches is first effected so as to bring the wrench 7 in the plane of the head of the bolt 9. Then through the loose connection of the double links 14 and 15 or the slotted link 17 the wrenches may be swung with 110 respect to each other to bring them into positions to engage the nut portions of the

members 9 and 11 and to allow the member 9 to be partially turned with respect to the member 11, if desired. The nuts 23 and 25 are then tightened up and with the wrenches 5 in proper position to hold the members 9 and 11 with one hand; the other wrench 13 may be used to tighten up the nut 12 with the other hand.

I desire it to be understood that the invention is not limited to any specific form or arrangement of parts except in so far as such limitations are specified in the claims.

What I claim as new and desire to secure by Letters Patent is:

15. 1. The combination, with a pair of wrenches provided with handles, of linkage connecting the handles of said wrenches together permitting them to swing and move bodily relatively to each other, one end of 20 said linkage having an adjustable spaced connection with one of the handles to dispose said wrenches in parallel planes.

2. The combination, with a pair of wrenches provided with handles, of linkage 25 connecting the handles of said wrenches together permitting them to swing and move bodily relatively to each other, one end of said linkage having a spaced connection

with one of the handles to dispose said wrenches in parallel planes. 30

3. The combination, with a pair of wrenches having integral handles, of a slotted link, means for adjustably clamping the slotted end of said link to one of the wrenches, and means for connecting the 35 other end of said link to the other wrench in spaced parallel relation therewith.

4. A device of the class described comprising a holding member, and a pair of wrenches carried thereby and capable of 40 ready adjustment angularly with respect to each other, said holding member having a pivotal connection with one of the wrenches and a slidable connection with the other wrench. 45

5. A device of the class described comprising a holding member, and a pair of wrenches carried thereby and capable of adjustment angularly and sidewise with respect to each other, said holding member 50 having a pivotal connection with one of the wrenches and a slidable connection with the other wrench.

In testimony whereof, I affix my signature.

PAUL C. BALDUS.
